UNITED STATES PATENT OFFICE.

ROSS B. MEEKER, OF SANFORD'S CORNERS, NEW YORK.

RAILROAD.

SPECIFICATION forming part of Letters Patent No. 269,442, dated December 19, 1882.
Application filed March 28, 1882. (No model.)

To all whom it may concern:

Be it known that I, ROSS B. MEEKER, of Sanford's Corners, Jefferson county, New York, have invented new and useful Improvements in Railroads, of which the following is a full, clear, and exact description.

The invention consists of metal ties, stay-bars, and joint-connections contrived for dispensing entirely with the wood ties now used, and for more substantial and durable construction; also greater facility of adjustment of the rails when desired; and also for greater strength in the rails, all as hereinafter more fully described.

Reference is to be had to the accompanying drawings, forming part of this specification, in which similar letters of reference indicate corresponding parts in all the figures.

Figure 1 is a plan view of a short section of railroad constructed according to my invention, with a part sectioned horizontally. Fig. 2 is a side elevation, and Fig. 3 is an end elevation.

A represents the rails, which I propose to make considerably higher in the web *a*, between the head *b* and base *c*, than usual, in order to have greater self-supporting power between the ties than as now constructed, so as not to require so many ties; but in order not to materially increase the weight I propose to make the said web, also the base and the head, lighter, preferring to dispense with some of the metal of these parts, or rather altering the proportions, and so disposing the metal as to increase the height of the web, and thereby making the rails stiffer. With the rails thus increased in carrying capacity I propose to use metal for the ties *B* and stay-bars *C* for greater permanence and durability; and the ties I propose to make of wide plates or bars of rolled metal, with a deep bend, *d*, downward along the middle, from end to end, for so stiffening a thin plate that it may possess the required rigidity, and also for forming a channel for the cross-bar *D*, set edgewise therein, for coupling the rails both crosswise and lengthwise; also for a means of vertical adjustment of the rails above the ties, in case they settle too low in the earth. These cross-bars *D* are made longer than the ties, and have the ends, which are increased in height to the top of the rails, from about the middle

of the latter, bent around against the ends of the ties, as shown at *e*, to afford hold in the earth against central displacement of the rails by the lower portion. Between the rails and these parts *e* the elevated portions *f* are designed for connecting the rail-joint angle-plates *g*, which are bolted to them by joint-bolts *h*, for which the holes *i* are slotted, so that the rails can be shifted upward and supported above the ties by the bolts, and by wood blocks inserted between them and the ties, if necessary.

Besides the bends *d*, the edges of the ties may be flanged over, as at *j*, to increase their stiffness. The cross-bars *D* are firmly secured in the grooves of the ties by rivets *k*, so that they add stiffness to the ties. Besides these ties, I also propose to employ metal stay-bars *C* as a means of safety against lateral displacement of the rails in case the bolts *k* should give way, said stay-bars having the outer ends, *l*, bent up over the flange outside and the lugs *m* similarly bent up over it inside, in the manner of switch-bars, to connect the rails securely together, so that although the joint coupling-bolts of each side may give way the rails *A* cannot separate nor shift toward each other out of line.

In practice I propose to place these stay-bars alternately with the ties, or two or more may be used, the ties only being employed at the joints, according to the length of the rails, and when the ties are used between the joints of the rails the stay-bars *C* may be omitted.

The form adopted for the ties is with special reference to the use of rolled plates; but I do not limit myself thereto, for cast metal may be used in some cases, if desired.

Having thus described my invention, I claim as new and desire to secure by Letters Patent—

1. The combination of a cross-bar, *D*, with a railroad-tie consisting of a flat bar or plate having a longitudinal grooved rib, *d*, said cross-bar being set edgewise in said grooved rib and riveted therein, substantially as specified.

2. The combination of the grooved and ribbed plate or bar-tie *B* *d* and cross-bar *D* with rails *A*, said cross-bar having the ends *e* bent, as described.

3. The combination of the grooved and ribbed plate or bar-tie *B* *d* and cross-bar *D*

with the rails, the said cross-bar having the vertical extensions *f* at and between the rail-joints, and the joint-plates *g* bolted thereto, substantially as specified.

5. The combination of joint-plates *g*, rails *A*, cross-bar *D*, and vertical extensions *f* of said cross-bar, the latter being provided with slotted holes for the joint-bolts *h* for adjusting the rails, as described.

10. 5. The combination of alternate grooved and

ribbed plate or bar-ties *B* and stay-braces *C* with rails *A*, substantially as specified.

6. The rails connected both lengthwise and crosswise by the cross-bar *D*, with vertical extensions *f*, joint-plates *g*, and bolts *h*, substantially as specified.

ROSS BARNEY MEEKER.
